UNITED STATES PATENT OFFICE.

THEODORE VARNEY, OF PITTSBURG, PENNSYLVANIA, ASSIGNOR TO WESTINGHOUSE ELECTRIC & MANUFACTURING COMPANY, A CORPORATION OF PENNSYLVANIA.

OVERHEAD LINE STRUCTURE.

946,624.

Specification of Letters Patent. Patented Jan. 18, 1910.

Application filed June 8, 1907. Serial No. 377,946.

To all whom it may concern:

Be it known that I, THEODORE VARNEY, a citizen of the United States, and a resident of Pittsburg, in the county of Allegheny and State of Pennsylvania, have invented a new and useful Improvement in Overhead Line Structures, of which the following is a specification.

My invention relates to overhead electric line structures and has special reference to such line structures as are adapted for relatively high-voltage railway service.

The object of my invention is to provide improved means for effectively supporting electric conductors particularly against lateral movement without involving the use of bracket arms.

It is often undesirable or impossible to employ a well known form of bracket arm suspension for electric railway supply lines, and various cross span structures have been employed in lieu thereof in the prior art. I have provided a cross span supporting structure which is specially adapted for use with a catenary suspension system supplied with energy at high voltage.

Figure 1, of the accompanying drawings is a view, in end elevation, of my improved cross span structure. Fig. 2 is a view at right angles to Fig. 1, and Fig. 3 is a view, similar to Fig. 1, of a cross span structure provided with a steadyng device for preventing lateral displacement of the conductor.

Referring to the Figs. 1 and 2 of the drawings, a trolley conductor 1 is suspended, in a well known manner, by hangers 2 from a messenger or supporting cable 3. The messenger cable is supported by and insulated from a cross bar 4 by means of a petticoat insulator 5 which is adjustably mounted thereon. The cross bar 4 may be in the form of a T-iron bar or a rod or bar of any other convenient section and is suspended from poles 6 and 7 or other stationary supports, located at the respective sides of the trolley conductor, by means of cables 8 and 9 that connect the respective ends of the rod or cross bar 4 to eye bolts 10 with which the poles are provided. Another cable 11 is hung from the eye bolts, at some distance above the messenger cable 3, and hangers 12 and 13 connect the ends of the rod 4 with the cable 11. The tension on the cross cables is such that the weight of the messenger cable 3 is divided between them.

Reference may now be had to Fig. 3 in which a cross bar or rod 14, that corresponds to the rod 4 of Figs. 1 and 2, is similarly suspended from a cross cable 15 by means of hangers 16 and 17 which correspond to the hangers 12 and 13 of the other figures. Instead of the cables 8 and 9, cables 18 and 19 are stretched from the ends of the rod 14, in a substantially horizontal line, to the supporting poles 20 and 21, and serve, in this instance, to steady the rod without bearing any of its weight.

The trolley conductor 1 may be supported against lateral displacement by means of a brace 22 which comprises an arm or rod 23 one end of which is secured to the trolley conductor by any convenient means such as a clamp 24 and the other end of which is secured to a sleeve insulator 25. This insulator is supported, in a well known manner, by a clevis or horse shoe bracket 26 that is adjustably mounted on a rod 11.

I desire that my invention shall not be restricted to the arrangement shown in the drawings and that only such limitations shall be imposed as are indicated in the appended claims.

I claim as my invention:

1. In an electric line structure, the combination with an electric line conductor, stationary side supports, a span wire or cable between each pair of said supports, a cross bar suspended from said wire or cable, and wires or cables between the ends of said cross bar and said supports, of a messenger cable supported by said cross bar and hangers for suspending the conductor from said messenger cable.

2. In an electric line structure, the combination with an electric line conductor, stationary side supports, a span wire or cable between each pair of supports, a cross bar suspended from said wire or cable, and wires or cables between the ends of said cross bar and said supports, of a petticoat insulator adjustably mounted on the cross bar, a messenger cable supported on said insulator, and hangers for suspending said conductor from said messenger cable.

3. In an electric line structure, the combination with an electric line conductor, stationary side supports, a span wire or cable between each pair of supports, a cross bar suspended from said wire or cable, and wires or cables between the ends of said cross bar

and said supports, of a petticoat insulator mounted on the cross bar, and a messenger cable and hanger rods for suspending said conductor from said insulator.

- 5 4. In an electric line structure, the combination with a messenger wire or cable, stationary side supports, a span wire or cable between each pair of supports, a cross bar suspended from said wire or cable and wires or cables between the ends of the cross bar and the supports, of a trolley conductor suspended from the messenger cable, and means for securing said messenger cable to the cross bar and insulating it therefrom.
- 10 5. In an electric line structure, the combination with stationary side supports, a span wire or cable between each pair of supports, a cross bar or rod suspended from said wire or cable, and wires or cables between the ends of the cross bar and the supports, and an insulator adjustably mounted on the cross bar, of a messenger cable or wire mounted on the insulator, and a trolley conductor suspended from the messenger cable below the cross bar.
- 15 6. In an electric line structure, the combination with stationary side supports, a cross bar or rod suspended from the sup-

ports, an electric insulator mounted on the cross bar, a messenger cable mounted on the insulator above the cross bar and a trolley conductor suspended from the messenger cable below the cross bar, of a bracket adjustably mounted on the cross bar, a sleeve insulator supported by said bracket and an arm or rod interposed between the insulator and the trolley conductor.

- 20 7. In an electric line structure, the combination with stationary side supports, a cross bar or rod suspended from the supports, an electric insulator adjustably mounted on the cross bar, a messenger cable mounted on the insulator above the bar and a trolley conductor suspended from the messenger cable below the cross bar, of a second insulator adjustably mounted on the cross bar and an arm or rod interposed between the second insulator and the trolley conductor.

In testimony whereof, I have hereunto subscribed my name this 29th day of May, 1907.

THEODORE VARNEY.
